UNITED STATES PATENT OFFICE

142,724

DESIGN FOR A PIN

Christopher L. Migliaccio, Providence, R. I.

Application April 9, 1945, Serial No. 118,921

Term of patent 3½ years

(Cl. D45—19)

To all whom it may concern:

Be it known that I, Christopher L. Migliaccio, a citizen of the United States of America, residing at Providence, in the county of Providence and State of Rhode Island, have invented a new, original, and ornamental Design for a Pin, of which the following is a specification, reference being had to the accompanying drawing, forming part thereof.

Fig. 1 is an edge view of a pin showing my new design, and

Fig. 2 is a face view thereof.

I claim:

The ornamental design for a pin, as shown.
